(57) **CLAIM**

The ornamental design for a scrolling lighting dimmer actuator, as shown and described.

DESCRIPTION

FIG. 1 is a front elevational view of the scrolling lighting dimmer actuator according to the present invention;

FIG. 2 is a rear elevational view of the scrolling lighting dimmer actuator;

FIG. 3 is a right side elevational view of the scrolling lighting dimmer actuator;

FIG. 4 is a left side elevational view of the scrolling lighting dimmer actuator;

FIG. 5 is a left side perspective view of the scrolling lighting dimmer actuator;

FIG. 6 is a right side perspective view of the scrolling lighting dimmer actuator;

FIG. 7 is a rear-right perspective view of the scrolling lighting dimmer actuator; and,

FIG. 8 is a rear-left perspective view of the scrolling lighting dimmer actuator.

The broken lines in the drawings depict environmental subject matter only and form no part of the claimed design.
